(57)

CLAIM

(71) Applicant: **Aluminium Architecture Institute Co., Ltd**, Tokyo (JP)

The ornamental design for a shelf, as shown and described.

(72) Inventor: **Naoto Fukasawa**, Tokyo (JP)

DESCRIPTION

(73) Assignee: **ALUMINUM ARCHITECTURE INSTITUTE CO., LTD.**, Tokyo (JP)

1.1: Front

(**) Term: **15 Years**

1.2: Back

(21) Appl. No.: **35/511,605**

1.3: Right

(22) Filed: **Sep. 25, 2020**

1.4: Left

(80) **Hague Agreement Data**

1.5: Top

Int. Filing Date: **Sep. 25, 2020**

1.6: Bottom

Int. Reg. No.: **DM/212186**

1.7: Perspective

Int. Reg. Date: **Sep. 25, 2020**

1.8: Cross sectional

Int. Reg. Pub. Date: **Mar. 26, 2021**

1.9: Cross sectional

(30) **Foreign Application Priority Data**

1.10: Cross sectional

The even spaced broken lines show portions of the shelf that

Primary Examiner — Mary Ann Calabrese

form no part of the claimed design, and the dash-dot broken

(74) Attorney, Agent, or Firm — Manabu Kanesaka

lines define boundaries of the claimed design and form no

part of the claimed design. Fig. 1.8 is a cross-sectional view

taken along the A-A line shown in fig. 1.1; Fig. 1.9 is a

cross-sectional view taken along the B-B line shown in fig.

1.1; Fig. 1.10 is a cross-sectional view taken along the C-C

line shown in fig. 1.1; Fig. 1.11 is an enlarged view between

D and D shown in fig. 1.4; Fig. 1.12 is an enlarged view

between E and E shown in fig. 1.4; Fig. 1.13 is an enlarged

view between F and F shown in fig. 1.9; Fig. 1.14 is enlarged

view between G and G shown in fig. 1.9; Fig. 1.15 is an

enlarged view between H and H shown in fig. 1.8; Fig. 1.16

is an enlarged view between I and I shown in fig. 1.8; Fig.

1.17 is an enlarged view between J and J shown in fig. 1.10;

Fig. 1.18 is an enlarged view between K and K shown in fig.

(Continued)

1.10; Fig. 1.19 is an enlarged view of an area L shown in fig. 1.17; and Fig. 1.20 is an enlarged view of an area M shown in fig. 1.18.
